COMBINED AUTOMATIC AND MANUALLY
OPERABLE CLUTCH ACTUATING MECHA-
NISMAugustus Parker-Smith, New York, N. Y., as-
signor to Bendix Products Corporation, South
Bend, Ind., a corporation of Indiana

Application January 21, 1932, Serial No. 587,847

17 Claims. (Cl. 192—01)

This invention primarily comprises an improvement upon the construction shown in the application of J. H. K. McCollum and H. J. DeN. McCollum, Serial No. 587,879 filed January 21, 5 1932. In said co-pending application an apparatus is disclosed in which a pneumatically operated power developing element, manually controlled, is employed for engaging and disengaging the clutch of a motor car, which power element 10 can be nicely graduated in its operation so as to hold the clutch at any intermediate point of engagement or disengagement. In one form of the invention therein disclosed the manually operated element is a separate pedal operated by 15 the driver's left foot. In another form therein disclosed the pressure controlling valve for the pneumatically operated element (in that case the vacuum cylinder) is connected to the pedal which also, during certain stages of its movement, controls the motor throttle so that the power controlling mechanism is then automatically timed with reference to the throttle movements. According to my present invention these 20 two types of apparatus are combined in one, so that the pneumatically operated power developing element (the vacuum cylinder and piston therein) can either be independently operated by the operator's left foot pressing on the special pedal provided for that purpose, or by the operator's right foot which rests on the accelerator operating pedal, and the movement of which, at a later or earlier stage of its movements, also controls the motor throttle. However, according 25 to the present invention, the mechanism operated by the left foot predominates in control over the power developing element so that at any time while said element is being automatically operated in conjunction with the accelerator, the driver can, if he desires, override such 30 automatic operation and independently modify the action of said power developing element. The invention also comprises a manually operable disconnecting mechanism between the two sets of apparatus above described, so that 35 the two can be completely disconnected when desired, thus leaving the throttle to be independently controlled by the right foot, through the agency of the pedal which operates the accelerator, while the power developing element can be 40 independently controlled by the left foot to engage or disengage the clutch at any time and to any extent which existing conditions may require.

The best form of apparatus embodying my invention at present known to me, together with

certain minor modifications thereof, is illustrated in the accompanying sheet of drawings in which

Fig. 1 is a diagrammatic view showing the preferred form of the apparatus, parts being broken away and others shown in section.

Fig. 2 is a detail showing on a larger scale two floating levers which are employed and their connections, in partly dissociated conditions, parts being broken away or shown in section, on line 2—2 of Fig. 3.

Fig. 3 is a detail on an enlarged scale of the preferred form of disengaging apparatus, technically called a "lockout" or a "cutout" device, by means of which the two sets of controlling apparatus can be entirely dissociated and the manually controlled device left free to be operated independently and in sole control of the power developing element.

Fig. 4 is a detail illustrating a modified form 20 of connection and for the manually operated power controlling connection.

Fig. 5 is a detail longitudinal section of the valve 10 looking from the side opposite that shown in Fig. 1.

Throughout the drawing like reference characters indicate like parts.

Fig. 1 illustrates generally the type of pneumatic, clutch-operating apparatus now coming into quite general use, the basic features of which 30 constitute no part of my invention, and also illustrates one form of special control apparatus therefor, of the type described in the above noted McCollum application. The portions of the apparatus above referred to may be described as 35 follows:

1 is the usual clutch operating shaft on which clutch lever 2 is rigidly mounted, carrying the clutch pedal 3 which projects through an opening in the footboard 4. A pivot pin 5 connects 40 said clutch lever to the piston rod 6 which is fast at its other end to the piston 7 reciprocating in the cylinder 8, which latter is pivoted at 8a to the chassis or other support, said pivotal connection being provided to accommodate the angularity of the swinging clutch lever 2. The conduit 9 connects the closed end of the cylinder 8 with the valve generally indicated by the reference character 10, which valve may be of the same construction as is shown in the said co-pending McCollum application, as clearly shown in Fig. 5. The other end of cylinder 8 is open to the atmosphere. The conduit 11 connects valve 10 with the intake manifold 12 of the motor car. The valve 10 is primarily operated by pedal 55

or button 18, mounted on plunger 16 pivoted at its other end at 17 to the floating lever 15, the fulcrum of which is provided by the pivot pin 21 which moves in unison with the movement 5 of the clutch lever 2. Said pin 21 might be rigidly mounted on said clutch lever, but to avoid the tipping action of said pivot pin, which would then result, I prefer to mount it upon a parallel motion mechanism consisting of the link 20, one 10 end of which is pivoted to said clutch lever at 5a, while the other end is pivoted to the collar 26 which slides freely on the piston rod 6. By this arrangement also the amplitude of motion transmitted to the said pivot pin 21 from the clutch 15 lever can be reduced to any desired extent, compared with that of clutch pedal 3, by locating the pivot 5a as near shaft 1 as may be necessary to create the reduction ratio required. The free 20 end of floating lever 15 is pivoted at 14 to the rod 13a, the other end of which is pivoted to an arm extending laterally from the stem 13 of the valve 10. As a result of the mechanism so far described the valve 10 can be moved to initially 25 open or close connection from cylinder 8 to the intake manifold 12, or to the atmosphere through the port 31, the opening of which latter can be adjusted by the screw plug 32. If, after any such initial movement of the valve has been thus manually produced the movement of button 18 stops, 30 the movement of the clutch lever 2 thereby caused shifts the position of the lever's fulcrum pin at 21, thereupon causing a reverse movement of the valve so that all valve ports are lapped and the parts held in the position then assumed, all as 35 described in said co-pending McCollum application. 19a is a compression spring normally forcing pedal or button 18 to the right or upward and so holding the valve stem 13 in a position which closes the connection from cylinder 40 to manifold and leaves the connection from cylinder to the atmosphere open, so that the clutch-actuating member 2 under the pull of spring 35 is then maintained in a position causing complete engagement of the clutch (not shown). It 45 should be understood that in the arrangement here shown the valve 10 is supposed to be held in fixed position (by some support not shown) and that the conduit 9 is made of light copper tubing which will bend sufficiently to accommodate 50 the slight oscillations of the cylinder 8 upon its pivot 8a though, of course, said valve might be mounted on the cylinder and the conduit 11 flexed when both valve and cylinder were oscillated.

55 Various forms of two-way valve other than that indicated at 10 might be used, provided always that the valve so substituted shall also be so made as to close communication with its air inlet port (such as indicated at 31) before it opens 60 the connection (such as shown at 11) to the intake manifold; and on reverse movement will close the manifold connection 11 before it opens air port 31, or other communication with the external atmosphere. Preferably also, a valve 65 should be used having a piston which, as shown, can slightly lap the ports connecting with conduit 9, which extends to the cylinder 8, so that a slight amount of travel of the valve is required after the suction has been cut off before air is 70 admitted to said conduit. This ensures the impossibility of the establishment at any time of a straight-through connection from air inlet to intake manifold ever being established. The reason for this provision, in addition to the resultant 75 advantage of its effectively holding piston 7

with certainty in any position in which it may have been stopped at the time the valve was moved into such mid position of port lapping, is that this construction prevents the inflow to the intake manifold of an undetermined, uncontrollable and unwanted amount of air which would, in many cases, make the fuel mixture temporarily so lean that the motor would stall. Such objectionable upsetting of the proper proportions of fuel mixture would occur every time the operator began to accelerate the motor from idling speed, which of course always has to be done whenever the car is started. The valve 10 is operated by the first movement of the accelerator and before the throttle is moved thereby. If, therefore, said valve opened the air inlet before the manifold connection was closed, that would cause a rush of air into the manifold while the carburetor was still idling, the throttle not then having been moved from idling position because of the lost motion connection 131, 138. This temporary excess of air, even if small in amount, would be so considerable relatively to the amount of air passing through the nearly closed throttle valve, and relatively to the amount of fuel being supplied by the idling jet, that an incombustible mixture would instantly be formed, and the motor thereby stalled.

While this stalling difficulty would occur in any type of clutch controlling unit operated by the sub-atmospheric pressure derived from the intake manifold, it would occur in an especially aggravated form in the species of such unit here shown because, for the purposes of this invention, the suction controlling valve must be and is continually shifted from slightly open to barely closed positions during manipulation of the clutch. If, therefore, during that short range of reciprocation of the valve, air was thus being almost continually passed through the valve to the manifold, and consequently a varying degree of vacuum, or no vacuum, was being transmitted to or created in cylinder 8, the clutch would stutter into and out of engagement, and the motor die as often as it was accelerated above idling speed. Obviously, therefore, any apparatus involving a valve having this objectionable double opening feature (such as some of those shown in the prior art) would be inoperative for the purposes of my present invention.

So far as above described, the apparatus is essentially that illustrated in Fig. 5 of the McCollum application, 35 being the usual spring which normally holds the clutch actuating member 2 in a position which will produce complete clutch engagement, and which after the clutch has been opened, returns such clutch lever to that position whenever the vacuum in cylinder 8 is released.

127 represents the carburetor for the motor of the car, having a butterfly throttle valve (not shown) mounted on the throttle shaft 128, which also carries the throttle lever 130. Normally the spring 131 holds said throttle valve in a position determined by the adjustment of the stop arm 129 carried by shaft 128 when the screw carried by said stop arm is in contact with the stop rib 129a. The throttle is operated by means of the accelerator rod 139 which has the telescoping, lost-motion mechanism 138 and 131, the free end of the rod 137 being pivoted to the throttle arm, 70 and the free end of the rod 139 being pivoted at 11a to the plunger rod 16a which projects through the footboard 4 and carries the button 18a, said element being normally held by spring 19b in a position of rest with the throttle closed to idling 75

position, a gap then existing in the lost-motion connection 137-138. A second floating lever 15a is also fulcrumed on the pin 21 at one end and at the other end is pivoted to the rods 16a and 139 by means of the pin 17a.

Obviously the mechanism last described enables the driver by pressure of his right foot on button or pedal 18a to operate the carburetor throttle in the manner common to practically all 10 motor cars as now constructed, and if there were no further connection between the two floating levers 15 and 15a, the pneumatically operated power developing element comprising the cylinder 8, piston 7 and their heretofore described 15 connections, would be left solely under control of the other pedal or button or equivalent manually operable device 18.

If, however, an operative connection is established between the two floating levers 15 and 15a, 20 the power developing apparatus can be alternately operated either by button 18, or 18a. In order to permit this to be done, however, without interfering with the throttle operation, which must take place during a portion of the travel of the 25 button or pedal 18a separate from the portion of the travel thereof which operates the valve 10, the connection between said floating levers must be a lost-motion connection, i. e. one which permits them to move together during the initial 30 downward motion of button 18a (that is, to the left, looking at Fig. 1) during which the valve 10 is operated, but thereafter allows the floating lever 15a to move freely during the continued 35 throttle operating portion of the travel of said button 18a.

The particular method of accomplishing this 40 here illustrated will be best understood by reference to Fig. 2, where 51 represents a "lockout" or "cutout" pin slidably mounted in the cup 52 which is screwed into the lever 15, as shown in detail in Fig. 3. When said pin is forced down so that its head 58 rests on the bottom of said cup, its lower end projects down into slot 50 formed in the rear side of the lever 15a. As a result, when 45 the spring 19b forces the accelerator operating button 18a back to the extreme right (looking at Fig. 1, i. e. into its position of rest, the pin 51 engages the bottom of said slot during the latter portion of the travel of lever 15a resulting from 50 such movements of button 18a (which occurs while the gap in the lost motion mechanism 137-138 is being opened) and the lever 15 (being thus locked to 15a) is thereby caused to oscillate on the common fulcrum 21 of both levers through 55 an angle sufficient to open the valve 10 in such manner as to afford communication from cylinder 8 to intake manifold 12, thereby pulling the clutch into disengaged position. Conversely, when the operator presses down on button 18a he oscillates 60 lever 15a in a counterclockwise direction on its fulcrum pin 21, and, though there is no positive connection between the two levers, a similar motion of 15 is thereby permitted, and in fact occurs, since spring 19a causes button 18 to move to 65 the right into dotted line position, thereby causing lever 15 to oscillate with lever 15a. Such motion of 15, of course, closes off the suction connection because of the consequent movement of valve stem 13. At the same time communication 70 to the air port 31 is established, the vacuum in cylinder 8 consequently dissipated, and clutch spring 35 causes the clutch to engage, just before the lost-motion between 137 and 138 has been taken up. Thereafter further movement of button 18a to the left merely causes floating lever 15a

to move away from pin 51 and leaves said button and its accelerator connections free to be moved back and forth to control the degree of opening of the throttle valve in the carburetor without moving lever 15 and valve 10, at all. Obviously, also, when the operator has released the pressure of his foot on button 18a up to a point which brings the lost-motion gap 137-138 just to the point of opening, lever 15a will have then become initially engaged with pin 51, and thereafter further movement of button 18a back to its position of rest will cause lever 15 to also oscillate on common fulcrum 21 in a clockwise direction, opening the connection from cylinder 8 to manifold 12 and pulling the clutch out of engagement, as previously described. If we assume that floating lever 15 has been removed, the last above described apparatus and operation will be essentially the same as those illustrated and described with reference to Fig. 6 of the McCollum co-pending application above referred to. It is only when the two levers 20 separately shown in separate arrangements (Figs. 5 and 6) of said McCollum application, are both employed, and with some such operative connection between them as is above described, that 25 the present invention comes into the picture.

In order to allow the above described operation of the present apparatus the spring 19a must be weaker than the spring 19b, if the ratio between the leverage arms of 15 is equal to the 30 ratio of the lever arms of 15a. In any case, whatever the leverage ratios, the spring 19a must be so graduated as to its expansive force with reference to that of spring 19b that it will exert a lesser effective pull on the combined lever 35 system with reference to the common fulcrum 21 than does the spring 19b, so that when pressure is removed from both 18 and 18a and a position of rest assumed, the spring 19b will have been expanded and the spring 19a compressed, as 40 indicated in full lines in Fig. 1, and it is only when the accelerator operating button 18a has been pressed downward far enough to actuate the suction controlling valve 10 that button 18 is allowed to rise to its highest position, which is 45 the broken line position shown in Fig. 1.

With the apparatus so described it is obvious 50 that the power developing element may be operated solely by movement of the accelerator actuating button 18a, so that its operation is automatically timed with reference to the throttle operation and thus produces free wheeling when the driver takes his foot off button 18a, but automatically throws the clutch into engagement before the throttle is opened beyond its idling position, and that during all this time the button 18 will remain stationary in its broken line position, or idly fall and rise during the clutch manipulation periods of travel of the button 18a. If, however, when the throttle is in some position of 60 power producing opening, due to a sufficient depression of button 18a, the driver desires to release the clutch so as to race his engine, as for the purpose of clearing out his carburetor or for any other reason, he can do this by pressing down 65 on the button 18, which will then open up a lost-motion gap between pin 51 and lever 15a, and independently operate valve 10, the connecting mechanism from button 18 to said valve being positive and continuous at all times, and thus 70 predominating over, or overriding, any control or release of said valve exerted by button 18a.

If, however, the throttle were thus open to any considerable extent the degree of vacuum in manifold 12 may have dropped to a point such 75

that it will not be able to overcome the resistance of spring 35, and pull the clutch open. Accordingly I prefer to insert the vacuum tank V, of relatively considerable capacity, in the conduit 11 between the valve 10 and the manifold 12, and to place a check valve W in the conduit between said tank and manifold, which valve opens toward the manifold, its opening motion being limited by the stop W'. When this tank is used the check valve will close whenever the degree of vacuum in manifold 12 drops below that in tank V', and a sufficient degree of vacuum will thereafter be carried over in said tank to operate the pneumatic power device (cylinder 8 and piston 7) one or more times so as to produce sufficient clutch disengagement, and the above suggested racing of the motor can be thereby produced, or the clutch power-operated under manual control at any time and for any purpose, independently of the position of the accelerator.

Also it may happen that some drivers will not care to have the automatic clutch control above described in operation at any time, or the automatic devices may get out of proper adjustment, so that it is desirable to disconnect them entirely and to leave the pneumatically-operated power-developing element solely under control of button 18 for manual operation. To render this possible I prefer to have the pin 51 slidingly mounted in the cup 52 mounted on lever 15 and normally held down in position such as to engage lever 15a by the pressure of spring 57 which is compressed between the pin head 58 and the cup cap 56, and then connect to said pin a Bowden wire 53 which is encased in the flexible sheath 59, both of which are extended up to the instrument board 54, where the wire terminates in a knob 55. The lower end of the sheath 59 is screwed into the cup cap 56, as shown in Fig. 3. When this attachment is installed the operator can at any time pull up on the button 55, thereby lifting pin 51 into the position shown in broken lines in Fig. 3, so that its lower end will no longer engage the walls of the slot 50 in lever 15a, and thereafter the floating lever 15a is operatively disconnected from the clutch controlling apparatus which is then left solely under control of the button 18. After such disengagement has occurred the button 18 will rise to the broken line position under action of the spring 19a and remain in that position shutting off the suction connection to cylinder 18 and leaving the clutch normally engaged until the operator causes its partial or entire disengagement by pressing down on said button 18. The friction between the wire 15 and sheath 59 is sufficient to hold "lockout" pin 51 in this elevated position against the expansive force of the then compressed spring 57. When, however, downward pressure is applied by the hand to button 55 the wire is forced down and pin 51 is no longer held up thereby.

Preferably the connection between the lower end of the wire 53 and the pin 51 is a collapsible one, such as afforded by the short length of chain 60, as indicated in Fig. 3. When this or other collapsible or flexible connection is used, and the button 18a is in fully retracted position when the "lockout" button 55 is pushed down, the pin 51 will merely be spring pressed down upon the upper surface of floating lever 15a which will then be in the broken line position indicated in Fig. 3, this relation of the parts being also indicated by the dotted circle in Fig. 2, but the next time the button 18a is depressed to operate the throttle

the slot 50 in 15a will move under pin 51 and spring 57 will force it down into the full line position shown in Fig. 3, thereby reestablishing the above described operating connection between the two floating levers and consequently between the two sets of control apparatus above described.

If, for any reason, the idle reciprocation of the button 18, when the apparatus is under control of the button 18a (in the manner hereinbefore referred to) is objectionable, it can be eliminated by the modified connection shown in Fig. 4, where the button plunger 16 has a pin-and-slot connection 17b to lever 15 in place of the simple pivot pin connection 17, and a third spring 19c is connected to floating lever 15 and anchored on the footboard. The spring 19c then performs the functions hereinabove ascribed to spring 19a in the arrangement shown in Fig. 1, and said spring 19a performs no other function than to hold button 18 normally in retracted position until said spring is compressed by the pressure of the operator's foot. In this arrangement, when the two levers 15 and 15a are operatively connected together by pin 51, the pin 50 of the lost motion connection 17a will reciprocate idly in the slot in plunger 16 during the clutch operating periods of travel of the accelerator operating button 18a, and whenever said button 18a has been pushed inward far enough 30 to begin operating the throttle the pin of 17a will have been brought to rest against the right hand end of said slot, and will be thereafter held there by spring 19c, the lever 15 then remaining at rest. Here again, however, if the operator 35 desires to open the clutch at any time while the throttle has been opened beyond its idling position, any downward pressure upon button 18 will move lever 15 and cause it to at once assume control of the valve 10 and thereby produce any 40 variety of clutch operation the operator may desire. In this modification spring 19c should exert a less effective pull on the system of levers than does spring 19b, and spring 19a need be only strong enough to hold button 18 in broken 45 line position, (i. e. raised) whenever said button is free from foot pressure.

Various other changes could be made in the details of the dual and separable control system above explained in principle, without taking 50 such further modified apparatus outside the scope of my invention. Also, other forms of lost motion mechanisms, or of one-way-operative connections might be substituted for those shown, and similar changes in details made 55 without eliminating from the resulting apparatus the substance of the invention as defined with varying degrees of breadth in the appended claims.

Having described my invention, I claim:

1. In a pneumatically operated clutch-actuating device for motor cars comprising a pneumatically operated power developing element connected to a movable clutch-actuating member, a valve for controlling said element, a carburetor throttle and motion transmitting mechanism by which the movements of said controlling valve and said throttle are automatically timed with reference one to the other so that the clutch is closed before the throttle is opened and only opened after the throttle has been closed to idling position, the combination, with said above described apparatus, of a manually operable device for moving said controlling valve; whereby said power developing element may be con- 75

- trolled either automatically or manually and in which said manually operable device predominates over said automatic means in the control of said power developing element, so that the 5 operation of the latter at any given moment may be determined by manipulation of said device, whatever the position of the throttle and of its timing means may be.
2. In a pneumatically operated clutch-actuating device for motor cars comprising a pneumatically operated power developing element connected to a movable clutch-actuating member, a valve for controlling said element, a carburetor throttle and motion transmitting mechanism by which the movements of said controlling valve and said throttle are automatically timed with reference one to the other so that the clutch is closed before the throttle is opened and only opened after the throttle has been closed to idling position, the combination, with 10 said above described apparatus, of a manually operable device for moving said controlling valve; whereby said power developing element may be controlled either automatically or manually and combined with manually operable mechanism for disconnecting said timing means from said controlling valve; whereby said power developing elements may then become subject to manual control alone.
3. In a vacuum-power clutch-operating apparatus for motor cars of the class described comprising a vacuum cylinder containing a piston connected to a clutch-actuating member, a valve controlling the degree of vacuum in said cylinder, a manually operable device, and a floating lever to which said clutch-actuating member, valve and manually operable device, are separately connected, the combination, with said above-described apparatus, of a second floating lever also 15 operatively connected to said clutch-actuating member and valve and to the pedal which actuates the accelerator for the motor of the car; whereby said valve may be opened and closed either by movement of said accelerator operating pedal or of said manually operable device.
4. A combination such as defined in claim 3 in which the connection from said second floating lever to said valve is manually disengageable.
5. A combination such as defined in claim 3 in which said floating levers have a common pivot which moves with said clutch-actuating member, the last mentioned lever being connected to the first mentioned one by a lost motion mechanism which leaves it free to move, independently of the first lever, with the accelerator when the latter is moving the motor throttle, and in which said vacuum controlling valve is directly connected to said first lever only.
6. A combination such as defined in claim 3 in which said floating levers have their adjacent end sections overlapping with a common pivot pin moving with said clutch-actuating member and passing through said overlapping lever sections, the first mentioned lever having a permanent connection to said controlling valve and carrying a pin adapted to engage one side of said second lever when the latter is swung on the common pivot toward said pin.
7. An apparatus such as defined in claim 3 in which said floating levers have their adjacent end sections overlapping with a common pivot pin moving with said clutch-actuating member and passing through said overlapping lever sections, the first mentioned lever having a permanent connection to said controlling valve and carrying

a pin adapted to engage one side of said second lever when the latter is swung on the common pivot toward said pin, and in which said pin is slidably mounted on the lever by which it is carried so as to be removable from the path of the other lever, combined with manually operable means for moving said pin into or out of said other lever's path.

8. An apparatus such as defined in claim 3 in which said cylinder and vacuum controlling valve are connected by a conduit also connected to the intake manifold of the motor, combined with a vacuum tank of relatively considerable capacity connected in said conduit line between valve and manifold, and a check valve in said conduit opening toward said manifold and located between it and said tank; whereby a sufficient degree of vacuum for disengaging the clutch will remain available for some time after the vacuum in the manifold may have been dissipated by a sufficiently wide opening of the throttle valve, or otherwise.

9. In an apparatus of the class described the combination of two levers having a common pivot near their adjacent ends, a pedal connected to the free end of each lever, a connection between said adjacent lever ends adapted to permit both pedals to be depressed at once, but to prevent both pedals being retracted at once, a power controlling element connected to one of said levers only, and separate springs normally tending to retract said pedals, the spring on the pedal connected to the controlling element being the weaker of the two in effective pull around the common pivot as a center.

10. In an apparatus of the class described the combination of two levers having a common pivot near their adjacent ends, a pedal connected to the free end of each lever, a connection between said adjacent lever ends adapted to permit both pedals to be depressed at once, but to prevent both pedals being retracted at once, a power controlling element connected to one of said levers only, and separate springs normally tending to retract said pedals, together with a third spring normally tending to swing said last mentioned lever in a direction toward its connected pedal, said spring being weaker than the spring on the other pedal in effective pull around the common pivot as a center, and said lever having a lost-motion connection to its pedal.

11. An apparatus such as defined in claim 3 in which said floating levers have their adjacent end sections overlapping with a common pivot pin moving with said clutch-actuating-member and passing through said overlapping lever sections, the first mentioned lever having a permanent connection to said controlling valve and carrying a pin adapted to engage one side of said second lever when the latter is swung on the common pivot toward said pin, and in which said pin is slidably mounted on the lever by which it is carried so as to be removable from the path of the other lever, combined with manually operable means for moving said pin into or out of said other lever's path comprising a Bowden wire extending from the instrument board of the car to said pin, and a spring normally forcing said pin toward said other lever.

12. In an apparatus of the class described the combination of two control levers for a clutch-actuating mechanism which have their ends superposed, a common fulcrum on which said superposed lever sections are pivoted, a pin slidingly mounted on one of said levers, a spring

normally tending to force said pin toward said other lever, a manually movable element for pulling said pin out of such engagement, and a collapsible connection from said element to said pin; whereby, if said element is placed in a position which would permit the pin to move into engagement with the other lever, but such pin movement is then temporarily prevented by an opposing surface of said second lever, the desired engagement will occur automatically whenever said opposing surface is slid away from contact with the pin end.

13. In a motor car controlling apparatus comprising a power operated mechanism for actuating the transmission clutch of the car, an accelerator pedal, and connections therefrom adapted to control said power operated mechanism, the combination, with said above described apparatus, of a second pedal and connections 20 therefrom also adapted to control said power operated mechanism, and manually operable means for disabling the first mentioned connection to said accelerator pedal and leaving said power operated mechanism under the sole control of said second pedal.

14. In a motor car controlling apparatus comprising a carburetor, throttle valve and accelerator pedal for actuating the same, a power transmission clutch and power operated mechanism for causing engagement and disengagement of said clutch manually controllable independently of said accelerator pedal, the combination,

with said above described apparatus, of a device connecting said mechanism with said accelerator pedal so that the former is automatically operated by the movement of the latter, and means for disabling said connection. 5

15. In a motor car controlling apparatus comprising a carburetor, throttle valve, accelerator pedal controlling said throttle valve, and spring means for retracting said accelerator to a position which closes said throttle valve to idling 10 position, together with a power transmission clutch and a separate pedal for actuating said clutch, the combination, with said above described apparatus, of a device operatively connecting said pedals together when said accelerator approaches the limit of its movement of retraction and adapted to then move said clutch pedal into clutch disengaging position.

16. An apparatus such as defined in claim 15 combined with means for disabling said device. 20

17. The combination of an internal-combustion engine, a vehicle driven thereby, a device jointly controlling the power of the engine and its driving connection with the vehicle, and positive mechanical means for disabling the control, by said device, of the driving connection without disabling its control of the engine power, said means being independent of operative connection to any other apparatus capable of exercising control over the vehicle's movements. 30

AUGUSTUS PARKER-SMITH.
